W. B. PARSELS

COFFIN RETAINING DEVICE FOR HEARSES

Filed April 1, 1924

١٤٦

Inventor,

William B. Pardee,

By Frank S. Aulemeny

Attorney

UNITED STATES PATENT OFFICE.

WILLIAM B. PARSELS, OF PLEASANTVILLE, NEW JERSEY.

COFFIN-RETAINING DEVICE FOR HEARSSES.

Application filed April 1, 1924. Serial No. 703,471.

To all whom it may concern:

Be it known that I, WILLIAM B. PARSELS, a citizen of the United States of America, and resident of Pleasantville, in the county ⁵ of Atlantic and State of New Jersey, have invented certain new and useful Improvements in Coffin-Retaining Devices for Hearses, of which the following is a specification.

¹⁰ This invention relates to the class of land vehicles, bodies and tops, and particularly to the class thereunder identified as coffin retaining devices for hearses.

¹⁵ An object of this invention is to provide a combined roller and coffin retaining device which is intended to facilitate the insertion and removal of a coffin with relation to a hearse, and prove effective to prevent lateral shifting of the coffin with relation ²⁰ to the rollers.

²⁵ It is a further object of this invention to produce an anti-shifting device operative without the employment of mechanically actuated means, and effective by reason of the weight of the coffin to prevent said shifting.

³⁰ It is a still further object of this invention to provide a device which is automatic in its action to prevent the shifting of a coffin, and of such character as to obviate the installation of mechanically operated devices for preventing said shifting.

³⁵ It is a well known fact that where provision is not made to guard against lateral movement of a coffin, they frequently shift sidewise until the sides of the coffin contact the guard rails and they then become abraded and damaged, a condition which this invention seeks to prevent.

⁴⁰ With the foregoing and other objects in view, the invention consists in the details of construction, and in the arrangement and combination of parts to be hereinafter more fully set forth and claimed.

⁴⁵ In describing the invention in detail, reference will be had to the accompanying drawings forming part of this application wherein like characters denote corresponding parts in the several views, and in which—

⁵⁰ Figure 1 illustrates a sectional view of a hearse body showing devices embodying the invention applied thereto;

Figure 2 illustrates a plan view of one of

the combined rollers and retaining devices; ⁵⁵ and

Figure 3 illustrates a perspective view of a fragment thereof.

In these drawings, no attempt has been made to illustrate parts of a hearse, except the parts with which the invention is related, and in the present embodiment of the invention, the hearse floor 5 has the usual roller 6 at the rear to facilitate the movement of the coffin as it is placed in or removed from the hearse. ⁶⁰ ⁶⁵

Furthermore, the hearse floor as conventionally made has a plurality of slots such as 7 in which anti-friction rollers are rotatably mounted to facilitate the manipulation of the coffin while it is being moved. ⁷⁰

In the present embodiment of the invention, the ordinary anti-friction rollers are omitted and combined anti-friction rollers and coffin retaining devices are substituted, one being placed in each of the slots 7. The ⁷⁵ rollers 8 of this invention have the usual trunnions 9 at the ends and the periphery of the roller has preferably a plurality of circumferential shoulders 10 arranged in pairs, the shoulders of each pair being oppositely faced. As here shown, there are two pairs of shoulders on each roller and the roller is beveled oppositely from each shoulder of a pair to form a relatively sharp edge 11 where the shoulder and beveled surface ⁸⁰ merge. These sharp edges are relied upon by the inventor to cut into or imbed themselves in the bottom of the coffin to a degree which will serve to anchor the coffin and prevent its sidewise movement with relation ⁸⁵ to the floor of the hearse. The roller also has a circumferential rib 12 at approximately its center, and the said rib has outwardly converging surfaces and a relatively sharp edge that will also produce a groove ⁹⁰ in the bottom of the coffin and aid in holding the coffin anchored.

The inventor does not wish to be limited with relation to the form of the anchoring projections, but in practice the form illustrated is believed to possess that strength and durability, as well as efficiency, which will render the device satisfactory in operation. ¹⁰⁰

The rollers have coffin supporting surfaces between the shoulders which serve to ¹⁰⁵

limit the depth of the groove in the bottom of the coffin.

I claim:

1. In a coffin retaining device, rollers adapted to support a coffin when in a hearse, each of the said rollers having circumferential shoulders integral therewith with relatively sharp edges, the said rollers having coffin supporting surfaces between the shoulders to limit the action of the edges of the shoulders on the bottom of the coffin, substantially as described.
2. In a coffin anchoring device, rollers adapted to be mounted in a hearse to support a coffin, the said rollers having pairs of shoulders on each side of the center oppo-

sitely faced, the said shoulders having relatively sharp edges, substantially as described.

3. A coffin retaining device comprising 20 rollers adapted to be rotatably mounted in a hearse, the said rollers each having pairs of shoulders on opposite sides of the center, the shoulders of each pair facing oppositely and having peripheral cutting edges, and an intermediate circumferential rib having its surfaces diverging from its periphery to its merger with the roller and a relatively sharp edge operative to produce a groove in the bottom of a coffin traveling thereon.

WILLIAM B. PARSELS.
